UNITED STATES PATENT OFFICE.

BENJAMIN THAW, JR., OF BUENOS AIRES, ARGENTINA.

TIME-CONTROLLED CIRCUIT.

Application filed December 30, 1925. Serial No. 78,326.

My invention relates to time controlled switches and particularly to a telephone circuit controlled by a time controlled switch.

5 My invention will be best understood from the following description when read in the light of the accompanying drawings of one specific embodiment of my invention selected for illustrative purposes, while the 10 scope of my invention will be more particularly pointed out in the appended claims.

In the drawings:—

Fig. 1 is a front view combined clock and time controlled switch constructed according to my invention;

Fig. 2 is a section on the line 2—2 of Fig. 1, also showing a schematic circuit diagram of a part of a time controlled telephone circuit; and

20 Fig. 3 illustrates a detail.

Referring particularly to Figs. 1 and 2, I have illustrated the cylindrical casing 1, which contains suitable clock work (not shown) for operating the hour hand 1 and 25 minute hand 3 of a clock, these hands traveling over the graduated clock dial face 5.

Herein the central portion of the clock face is cut away to provide a cylindrical opening 7 which receives the cylindrical 30 walls of a cup 9, which preferably is made of insulating material. Carried on the rearward side of the clock face, I have illustrated studs 11 provided with annular 35 grooves 13 in which are received the annular bead 15 formed on the cylindrical wall of the cup 9 so that the latter will be supported for rotation relatively to the clock face. Interiorly of the cup 9, I have illustrated a lever 17 fulcrumed on a pin 19 carried by the bottom of the cup, the lever at 40 its outer end carrying a contact 21. This lever conveniently is made of metal so that the contact will be in electrical communication with the pin 19. Also on the bottom 45 of the cup, I have herein provided a second contact 23 against which the contact 21 is adapted to rest when the lever is moved downwardly as viewed in Fig. 1.

On the under portion of the lever 17, I 50 have herein provided an arm 25 having a notched end 27 which receives the end of a spring 29 carried by a pin 31 secured to the bottom of the cup 9. The notch 27 is arranged with relation to the pins 31 and 19 55 so that in the position of the parts illustrated

by Fig. 1 the notch is at one side of a line connecting the pin 19 to the pin 31, thereby causing the spring in this position of the parts to hold the contact 21 out of contact with the contact 23. If the lever is pushed 60 downwardly, as soon as the notch 27 passes the line connecting the pins 19 and 31 the spring will move the lever until the contact 21 rests against the contact 23. Acting as a 65 limit stop for the upward movement of the lever, I have herein illustrated a projecting pin 33 carried by the bottom of the cup and against which pin the upper side of the lever rests when the lever is in the position shown by Fig. 1.

For actuating the lever, I have herein shown the hour hand provided with a pin 35 projecting into the cup 9 and the lever as provided with a cam surface 37 in the path if the pin when the switch is open, so that 70 when the hour hand moves the pin 35 against the cam surface 37 it will push the lever 17 downwardly until the notched portion 27 of the lever passes the line connecting the pin 19 to the pin 31, whereupon the spring 80 will cause the lever to move downwardly to bring the contact 21 against the contact 23 and maintain it there. Preferably the parts are so arranged that when the switch is thus closed the cam surface 37 is out of the path 85 of the pin 35 so as to permit unobstructed movement of the hour hand.

Any convenient means may be provided for opening the switch, and for this purpose I have herein indicated the end of the lever 90 17 as provided with a finger piece 38 by means of which the operator may raise the lever to the position of parts shown by Fig. 1 and open the switch. For permitting access to the lever, I have shown the frame 39 95 carrying the glass face 41 of the clock as hinged at 43.

For establishing electrical communication between the contacts and the exterior of the casing 1, I have shown a pair of rings 45 100 and 47 mounted on the back of the cup 9, the contacts 23 in any convenient manner being placed in electrical communication with the ring 45 and the pin 19 in electrical communication with the ring 47, as for example 105 the pin 19 may have a screw threaded end 49 which extends through the bottom of the cup 9 and is screwed into the ring 47 as indicated in Fig. 3, and the contact 23 may by 110 similar means be placed in electrical commu-

nication with the ring 45. Interiorly of the casing 1, I have shown a bracket 51 which preferably is made of insulating material and which carries a pair of brushes 53, 55 which respectively are in wiping contact with the rings 45 and 47. These brushes respectively are placed in electrical communication with binding posts 57, 59 by means of wires 61, 63, the binding posts conveniently being supported in insulating bushings 65.

For rotating the cup 9 and the switch mechanism contained therein relatively to the hour hand I have shown the cup provided exteriorly with gear teeth 67 which mesh with a pinion 69 rotatably supported on the shaft 71 having an operating knob 73 at the back of the casing 1. Suitable means may be provided for holding the cup 9 in its adjusted position, and for preventing rotation of the cup anti-clockwise, and herein I secure both of these results by means of a spring pawl 75 carried by the casing and cooperating with the teeth of the pinion 69.

In Fig. 2, I have illustrated the switch as applied to the ringing circuit of a subscriber's telephone. The bell at the subscriber's station is indicated at 77, while the ringing key and the battery at the central station are respectively indicated at 79 and 81. In one of the leads to the bell at the subscriber's station, herein the lead 83, is inserted the time controlled switch, and it will be observed that so long as the switch is open the bell cannot be rung. This allows the subscriber for instance, upon going to bed at 10 p. m., to move the cup 9 until the pointer 85 on the cup is opposite the hour mark VIII, and then open the switch, which insures for the subscriber that the telephone will not ring to interrupt his sleep until eight o'clock next morning. If desired, the time controlled switch may be provided with a short circuiting arrangement for placing it out of operation, and for this purpose I have herein indicated the manually controlled switch 87.

Although I have described for purposes of illustration one specific embodiment of my invention, it is to be understood that I am not limited thereby to its particular mechanical details but that wide deviations may be

made therefrom without departing from the spirit of my invention.

I claim—

1. A device of the character described having, in combination, a clock face, an hour hand moving relatively to said face, switch mechanism comprising a pair of relatively movable contacts, a lever carrying one of said contacts for movement relatively to the other for placing the contacts in open and closed relation, a spring for actuating said lever, means actuated by said hour hand for effecting release of said spring comprising a part pushed by said hour hand, said part being moved out of the path of said hour hand when said contacts are in closed relation, and a support for said lever, spring and contacts rotatable relatively to said hour hand.

2. A device of the character described having, in combination, a clock face, an hour hand moving relatively to said face, switch mechanism comprising a pair of relatively movable contacts, a lever carrying one of said contacts for movement relatively to the other for placing the contacts in open and closed relation, a spring for actuating said lever, means actuated by said hour hand for effecting release of said spring, and a support for said lever, spring and contacts rotatable relatively to said hour hand.

3. A device of the character described, having in combination, a clock face, an hour hand movable relatively to said face, a pair of contacts, a lever carrying one of said contacts, means carried by said hour hand for actuating said lever, said lever when said contacts are in contact being out of the path of said means carried by said hour hand and when said contacts are separated being in the path of said means, a spring connected to said lever at a point positioned to be at one side of the fulcrum of said lever when said contacts are in contact and at the opposite side of said fulcrum when said contacts are in separated relation; and means rotatable relatively to said hour hand supporting said contacts, lever and spring for rotation relatively to said hour hand.

In testimony whereof, I have signed my name to this specification.

BENJAMIN THAW, JR.
